UNITED STATES PATENT OFFICE.

SAMUEL H. SCHREIBER, OF NEW YORK, N. Y.

DESIGN FOR AN ORNAMENTAL STOCK FOR COMBS OR SIMILAR ARTICLES.

43,906.

Specification for Design.

Patented Apr. 22, 1913.

Application filed February 1, 1913. Serial No. 745,748. Term of patent 3½ years.

To all whom it may concern:

Be it known that I, SAMUEL H. SCHREIBER, a citizen of the United States, residing in the borough of Manhattan, city, county, and State of New York, have invented a new, original, and ornamental Design for Ornamental Stock for Combs or Similar Articles, of which the following is a specification, reference being had to the accompanying drawing, forming part thereof.

The figure is a front elevation of the decoration, showing my new design.

I claim:

The ornamental design for ornamental stock for combs, or similar articles.

SAMUEL H. SCHREIBER.

Witnesses:

GEO. WM. MIATT,
LILLIA MIATT.
